J. B. MOFFAT.
CARPET.

No. 20,596.

Patented Mar. 24, 1891.

UNITED STATES PATENT OFFICE.

JOHN B. MOFFAT, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,596, dated March 24, 1891.

Application filed February 7, 1891. Serial No. 380,652. Term of patent 3½ years.

To all whom it may concern:

Be it known that I, JOHN B. MOFFAT, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of groups of flower and leaf and branch forms somewhat conventionalized and scattered branch forms, all upon a shaded ground.

What I claim as new, and desire to secure by Letters Patent, is—

A design for carpets, consisting of the design substantially as shown.

JOHN B. MOFFAT.
